UNITED STATES PATENT OFFICE.

HENRY B. BEACH, OF MERIDEN, CONNECTICUT.

DESIGN FOR A NAPKIN-RING.

SPECIFICATION forming part of Design No. 22,947, dated December 5, 1893.

Application filed October 14, 1893. Serial No. 488,169. Term of patent 3½ years.

To all whom it may concern:

Be it known that I, HENRY B. BEACH, a citizen of the United States, residing at Meriden, in the county of New Haven and State of Connecticut, have invented a certain new and original Design for Napkin-Rings; and I do hereby declare the following to be a full, clear, and exact description of the invention, such as will enable others skilled in the art to which it appertains to make the same, reference being had to the accompanying drawings.

This invention relates to a new and original design for "napkin rings" and it consists in the ornamental configuration hereinafter described and shown in the accompanying drawings, wherein—

Figure 1 shows a ring embodying the design, and Fig. 2 is an elevation of the design in the flat.

The central portion of the ring is a band

which has a finished surface on which a shield with fanciful surrounding decorations is engraved. On the opposite edges of the central band borders or edgings which consist of the connected series of fanciful open work scrolls. ²⁵

The essential feature of the design is the open work borders consisting of a connected series of fanciful scrolls arranged on opposite sides of a central band.

Having thus described my invention, what is claimed as new, and desired to be secured by Letters Patent, is—

The design for a napkin ring substantially as herein shown and described.

In testimony whereof I affix my signature in presence of two witnesses.

HENRY B. BEACH.

Witnesses:

GEO. B. HOWARD,
I. E. BEACH.
